CLAIM

USPC **D15/29**; D15/28

The ornamental design for an adapter for a ground engaging machine implement, as shown and described.

(58) **Field of Classification Search**

DESCRIPTION

USPC D15/11, 28, 29; 37/456, 452, 450, 446, 37/454, 449, 453, 455, 903; 403/379.5, 403/DIG. 1; 111/152; 172/724, 730, 172/766, 770, 771, 721, 713, 699, 772
CPC Y10T 29/49826; Y10T 403/589; Y10T 403/7018; Y10T 403/7075; E02F 9/28; E02F 9/2825; E02F 9/2833; E02F 9/2866; E02F 9/2858; E02F 9/2808; E02F 9/2841
See application file for complete search history.

FIG. 1 is a front perspective view of an adapter for a ground engaging machine implement showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

Grayscale shading illustrates contour.

The broken lines illustrate structure or features which form no part of the claimed design.

The dot-dash broken lines illustrate a boundary which forms no part of the claimed design.
